CLAIM

The ornamental design for an electric egg fryer as shown and described.

DESCRIPTION

FIG. 1.1 is a front view of a base station for robotic vacuum cleaners

FIG. 1.2 is a rear view

FIG. 1.3 is a left view

FIG. 1.4 is a right view

FIG. 1.5 is a top view

FIG. 1.6 is a bottom view

FIG. 1.7 is a perspective view

The broken lines shown are included for the purpose of illustrating and form no part of the claimed design.
